(57) **CLAIM**

The ornamental design for a cover for rodent bait station, as shown and described.

DESCRIPTION

FIG. 1 is a front, right perspective view of a cover for rodent bait station, shown installed on a rodent bait station, depicting my new design;

FIG. 2 is a top view of the cover for rodent bait station depicted in FIG. 1;

FIG. 3 is a bottom view of the cover for rodent bait station depicted in FIG. 1;

FIG. 4 is a bottom view of the cover for rodent bait station depicted in FIG. 1, shown with the front flap open for insertion of a rodent bait station;

FIG. 5 is a right side view of the cover for rodent bait station depicted in FIG. 1;

FIG. 6 is a left side view of the cover for rodent bait station depicted in FIG. 1; and

FIG. 7 is a front view of the cover for rodent bait station depicted in FIG. 1; and,

FIG. 8 is a rear view of the cover for rodent bait station depicted in FIG. 1.

The broken line showing of a rodent bait station in FIG. 1 depicts the environment of the cover for rodent bait station and forms no part of the claimed design. The broken line showing of closing strips for closing the front flap in FIGS. 1 and 4 depicts portions of the cover for rodent bait station that form no part of the claimed design.
